UNITED STATES PATENT OFFICE.

EDOUARD MARIE QUELLENNEC, OF PARIS, FRANCE.

SELF-PROPELLED PLOWING-MACHINE.

1,108,787.

Specification of Letters Patent. Patented Aug. 25, 1914.

Application filed April 30, 1910. Serial No. 558,562.

To all whom it may concern:

Be it known that I, EDOUARD MARIE QUELLENNEC, of 10 Rue de la Chaise, Paris, France, engineer, have invented a new and useful Improvement in Self-Propelled Plowing-Machines, which improvement is fully set forth in the following specification.

This invention relates to self propelled plowing machines or diggers in which the 10 revolving tines or diggers can be made to penetrate more or less deeply into the soil or be taken out of action when traveling along a road.

The improvements relate more particularly to the method of suspending and driving the harrowing or digging tools and regulating and controlling the depth of tillage.

In the accompanying illustrative drawings: Figure 1 is a side elevation of a machine embodying my invention; Fig. 2 is a plan thereof, some of the parts being removed; Figs. 3 to 6 are respectively a side elevation, a plan and a section at right angles to the axes and a section through the axes of the mechanism by means of which the driving chains act upon the harrowing or digging tools. Fig. 7 shows a detail.

1 is a harrow or digger of the type for example shown in my application Serial No. 558,561, of even date herewith, carried by a horizontal shaft 2 suspended at each end on an arm 3. The arms 3 turn about a shaft 4, carried by the frame 5 of the machine and situated between the front and rear wheels 6 and 7. At a certain distance from its point of attachment to the frame, each arm 3 is provided with a hollow shell 8, perforated at its upper end to give passage to a rod 9 having upon it a rack 10. Along the 40 rod 9 slides a part 11 rounded at its upper end so that it may function as a swivel and suitably bear at all positions of the rod 9 against the concave surface of the shell 8. The lower surface of the piece 11 bears 45 against a strong spring 12 which bears against a sleeve 13 retained by the head 14 in which the lower end of the rod 9 terminates. The racks 10 mesh with pinions 15, each keyed to the end of a horizontal shaft 16, carried by the frame 5. Upon the frame 5 is also mounted a motor 17, Fig. 1, driving through a suitable change speed gear 18, a shaft 19 carrying at each end a chain wheel 20. A chain 21 connects each wheel 20 to another wheel 22 keyed to an intermediate shaft 23. In Fig. 1 the motor is arranged longitudinally, but it may be arranged trans-

versely, movement to the shaft 23 being then transmitted by other suitable gear. The shaft 23 carries a toothed wheel 24 which meshes with a toothed wheel 25 fast with the shaft 4.

To the shaft 4 and at each end of the same is fixed a chain wheel 26. The wheels 26 are each connected by a chain 27 to a wheel 28 keyed to the shaft 29, mounted in such a manner as to be able to rotate in a casing 30 carried by the shaft 2 around which the casing can oscillate. The shafts 29, each carry a pinion 31 which pinions mesh with 70 toothed wheels 32 fast with the shaft 2. The casings 30 are provided at their upper ends with a handle 33 which allows them to be oscillated in one direction or the other around the shaft 2 for the purpose of setting 75 the chain 27 at a suitable tension. The casings can be kept rigid in the required position by means of slides 34 jointed at 35 to the arm 3; tightening bolts 36 slide in a groove in said slides and are moreover provided with heads which pass into slots in the casings 30. The slides 34 carry on their face situated near the casing, teeth 37 into which mesh corresponding teeth on the casing. By loosening the bolt 36, the two sets 85 of teeth can slide upon each other without entering into engagement. When, on the contrary, the bolt is screwed up (the casing being in the required position) it is rendered completely rigid. The shaft 23 also carries 90 a toothed wheel 38, which gears with a wheel 39 on a shaft 40, mounted in a casing 41, carried by the frame 5. Upon the shaft 40 is mounted idly a bevel pinion 42, which gears with a bevel wheel 43, keyed on a 95 horizontal shaft 44, also mounted in the casing 41 at right angles to the shaft 40. A prolongation of the shaft 40 carries a hollow pivot 45, upon which turns idly a bevel pinion 46, also meshing with the wheel 43. The 100 pinion 42 is provided with catches 42^a and the pinion 46 with catches 46^a. A rod 47 guided in such a manner as to be able to turn in the pivot 45 and penetrating within the shaft 40 which drives it, carries a sleeve 105 48 provided with clutches which can be put into gear either with the pinion 42 or with the pinion 46, which has for effect to drive either one or the other of these pinions, thus imparting to the shaft 44 a movement of rotation in one direction or the other. The rod 47 may be moved by an oscillating lever 49 through connecting rods 50 and a lever 51 all controlled by a handle 52. The shaft

44 actuates through the intermediary of a speed reducer 53 and a worm 54, a worm wheel 55 keyed to the shaft 16 which also carries the pinion 15 as above described. By 5 moving the lever handle 52 in one direction or the other, the wheel 55 and consequently the pinions 15 are rotated in one direction or the other, and the rods 9 move upward or downward through their racks 10. These rods thus raise or lower the harrow 1 through the arm 3, the chains 27 preserving the same degree of tension because the axis 15 of oscillation is also that of the shaft of the wheels 26 over which the chains pass; there is thus a convenient and rapid means of raising or lowering the tines or digger tools. The racks 10 are maintained in contact with the pinions 15 by means of rollers 56, each fast with one arm of a fork 57 rocking on 20 the pinion shaft 16, so that the rollers 56 can follow all the movements of the racks 10. Lastly the whole assemblage, arm 3, shaft 2 with harrow 1 and rods 9 with racks 10, is guided by the aid of the curved grooves 58, 25 which have their centers at 4 and in which engage the heads of the pins 59 fixed to the arms 3.

Upon the shaft 44 is keyed a chain wheel 60 connected by a chain 61 to a wheel 62, 30 mounted upon a shaft 63, parallel to the shaft 44 and carried by the frame 5. At its other end the shaft 63 has upon it a small bevel pinion 64 gearing with another bevel pinion 65, fast with a vertical screw 35 threaded rod 66 along which can move an indicator nut 67, which moves in front of a scale 68. The movements of the indicator 67 being proportional to the movements of the arm 3 and of the harrow, this 40 indicator always shows the position of the tines. The driver can therefore regulate the depth of tillage and constantly control it without moving from the machine; he may also raise for a moment the tines in order to 45 avoid an obstacle encountered in working the soil and lower it immediately afterward to the depth required.

The jointing of the arm 3 to the frame 5, between the two axles reduces to a great 50 degree the amplitude of the movements due to the inequality of the ground, and the method of suspending the harrow upon springs as above described gives it sufficient liberty to follow the inequalities of the soil 55 and even to give if necessary to an obstacle formed by a body too solid or too hard to be cut or removed.

As the arms 3 are jointed to the frame 5, outside the rear wheels, the plowing device 60 or assemblage of digger tools as a whole may be given as great an axial length as desired and in all cases a length greater than the distance between the outer edges of the

flanges of the wheels which obviates the necessity of the wheels passing over tilled 65 soil.

The arrangements described are only given by way of illustration and may be largely modified, for example between the shaft 23 and the shaft 4 actuated thereby, 70 there may be interposed an arrangement allowing the speed of rotation of the tines to be modified according to the speed of the vehicle, the conformation of the ground to be tilled, etc. 75

Having now particularly described and ascertained the nature of my said invention and in what manner the same is to be performed, I declare that what I claim is:—

1. In a self-propelled plowing machine, 80 the combination, with a vehicle, a pair of side arms fulcrumed on the vehicle to swing in a vertical plane, a rotary digger shaft journaled in the side arms, diggers on said shaft and a motor arranged to propel the 85 vehicle, of means for driving the digger shaft from said motor, a rack swiveled to each side arm, gears engaging said racks, a shaft on which both gears are mounted, a worm-wheel on said shaft, a worm engaging 90 said worm-wheel, a reversing gear transmission mechanism intermediate said motor and the worm and arranged to drive the latter, manually controlled means for throwing the reversing gear transmission mechanism 95 into or out of operation, a screw-threaded rod, means for driving said rod at a speed proportional to the speed of the rack-engaging gears, a nut on the screw-threaded rod, and a level or position indicator actuated by the said nut whereby the relative 100 height of the diggers is indicated.

2. In a self-propelling plowing machine, the combination, with a vehicle, side arms 105 fulcrumed thereon, a rotary digger journaled in said side arms, and a gear-wheel mounted in a side arm and arranged to drive the digger, of a casing adjustable about the axis of the said gear-wheel, a chain-wheel and gear-wheel connected to 110 each other and carried by the casing, the two gear-wheels being in mesh with each other, a motor arranged to propel the vehicle, a chain-wheel carried by the vehicle and arranged to be driven by the motor, a 115 chain connecting the two chain-wheels, and means for securing the casing in any position to which it may be adjusted, whereby the tension of the chain may be adjusted.

In testimony whereof I have signed this 120 specification in the presence of two subscribing witnesses.

EDOUARD MARIE QUELLENNEC.
